(57) **CLAIM**

The ornamental design for a laboratory device, as shown and described.

DESCRIPTION

FIG. 1 shows a front perspective of a laboratory device with a lid thereof in a closed configuration;

FIG. 2 shows a front elevation view of the laboratory device of FIG. 1;

FIG. 3 shows a rear elevation view of the laboratory device of FIG. 1;

FIG. 4 shows a right elevation view of the laboratory device of FIG. 1;

FIG. 5 shows a left elevation view of the laboratory device of FIG. 1;

FIG. 6 shows a top plan of the laboratory device of FIG. 1; FIG. 7 shows a bottom plan of the laboratory device of FIG. 1; and,

FIG. 8 shows a front perspective view of the laboratory device of FIG. 1 with the lid thereof in an open configuration.

All of the broken lines in the accompanying drawings illustrate portions of the laboratory device that form no part of the claimed design.
